W. BIXBY

YARN SPOOL SUPPORT

Filed Nov. 6, 1923

Inventor:
Walter Bixby
by
Geo. N. Goddard, Atty.

UNITED STATES PATENT OFFICE.

WALTER BIXBY, OF BOSTON, MASSACHUSETTS, ASSIGNOR TO SHAWMUT ENGINEERING COMPANY, OF BOSTON, MASSACHUSETTS, A CORPORATION OF MASSACHUSETTS.

YARN-SPOOL SUPPORT.

Application filed November 6, 1923. Serial No. 673,054.

This invention relates to tube frames, such as are commonly used in tuft weaving Axminster carpets or similar fabrics, and is particularly concerned with providing a support for the journals of the yarn-spool of a type that is movable laterally to permit withdrawal of the yarn-spool while normally maintained in operative position for supporting the spool, without endwise pressure on the spool.

The particular application of the present improvement, in the form illustrated in the drawings, is to the middle or intermediate bearing member of the tube frame yarn-spool which is made in two or more sections placed end to end with their adjacent journals interlocked in any suitable well-known manner to secure uniformity of location of the several sections.

Generally speaking the invention comprises a supporting base member on which is fulcrumed a bearing arm provided at its free end with a journal bearing and at its fulcrum end with stop members disposed on opposite sides of the fulcrum axis, and engaged by the spring which, by equal pressure on both stop members, acts to maintain the bearing arm in operative position while allowing said bearing arm to be swung to either side to effect disengagement between the bearing and its contained journal when removing the spool. Since the bearing arm, although normally maintained in operative position, can yield in either direction for the purpose of inserting or removing the spool sections, the same construction may be used on either a right hand or a left hand construction.

These and other features of the invention will be explained in the following specification and will be defined in the claims hereto annexed.

In the accompanying drawings I have illustrated the tube frame equipped with my aforesaid improvements, in which:

Figure 1 is a front elevation of a tube frame having a two-part spool provided with my improved spool-supporting member.

Figure 2 is a plan view of the pivotal bearing arm and its base.

Figure 3 is a detail thereof in central vertical section.

Figure 4 is a front elevation with one portion of the bearing arm shown in cross section.

Figure 5 is an end elevation of the bearing member and base.

Figure 6 is a detail view showing in cross section a modified construction of stop member for the brake arm.

Figure 7 is an end elevation of the bearing arm containing the modified construction shown in Figure 5.

In the practice of my invention, according to the form illustrated in the drawings, the general tube frame construction is of the usual type and embraces a carrier bar 1, to the side of which is secured the tuft-guiding tubes or quills 1^a, said carrier bar being supported by usual suspension arms 2 and 3 at each end arranged to releasably engage the usual carrier chain, not herein shown. The frame is also provided with rigid spool-bearing arms 4, for the outside journals of the spool sections.

The spool 5 with its heads 6 and its outer journals 5^a, 5^b, is rotatably supported in these spool arms 4, while the inner journals of the yarn-spools are supported in an intermediate bearing member 8 which, in this case, comprises a pair of pressed steel arms formed with registering bearing apertures whose edges are outwardly turned to form shallow, aligned flanges 9 which form bearing seats for the adjacent journals 5^c, of the two spool sections which are of usual well known construction.

The intermediate bearing arm or spool-support 8, is fulcrumed on a fulcrum pin 12, which is mounted in a strap-like or base member 13, whose middle portion is formed into an upwardly projecting loop 14 to receive and support the ends of the fulcrum pin 12. The central portion of the base member 13 is cut out to form an elongated aperture or slot, as shown at 13^a, of slightly greater width than the flat spring 15 which is placed over said opening to overlap the end edges of said opening, the ends of the spring being of sufficient length to pass beneath the heads of the fastening screws 14 which attach the base 13 to the top of the carrier bar 1.

At their lower ends the similar plates forming the bearing arm 8, are cut and bent to form hinged eyes or loops 10, embracing the fulcrum pin 12 adjacent to the pin-supporting eyes 14, while the intermediate end portions between these loops forming the eyes 10, are carried downward astride of the

fulcral pin 12, as shown at 11 in Figure 3, their ends being proportioned to abut against the surface of the flat spring 15 so as to press firmly against said spring which acts with equal pressure on both stop members 11 to normally maintain the bearing arm in vertical operative position for supporting the adjacent journals 5° of the spool sections, while allowing the bearing arm 8 to be 10 swung to either side, the spring yielding sufficiently to allow such movement endwise of the spool, while acting to automatically return the bearing arm to operative position, when the arm is swung a short distance from perpendicular or operative position, owing to the fact that in such oblique position the unbalanced thrust of the spring is against the lower of the two stop members.

In Figures 6 and 7 I have shown a slightly modified construction of the hinge or fulcral joint in which the eyes or loop members embracing the fulcral pin 12 are extended to also form the stop members, which may be given any desired length to increase the leverage of the spring upon their ends. In this case the lower end of one member of the arm 8, as shown at 20 in Figures 6 and 7, is bent around the fulcral pin and extended in parallelism with the plane of the spring 15 to form separate stop members 20, which may be of any suitable length. The intermediate portion 21 of the other member of the arm 8 is likewise bent around the adjacent side of the fulcral arm, and extended 25 in parallelism with the leaf spring 15, to form a stop member on the opposite side of the fulcral axis. These two looped tongues or hinge members combined form a closed eye or bearing-receiving fulcral pin, 30 and provide, on opposite sides of the fulcral axis, stop members having engagement with the yielding spring 15, each of which acts in a direction opposite the other, and both acting normally to maintain the bearing arm 35 in operative position.

One great advantage resulting from this construction and arrangement of the intermediate spool bearing arm is that it permits the arm to be laid flat in substantial parallelism with the top of the carrier bar when the tube frame is being threaded, thus affording no obstruction to those tuft elements or threads which come opposite the intermediate bearing member. Hence the threading needles can pass through directly to engage the clamp-held thread ends for the threading operation without any interference or obstruction.

What I claim is:

1. A bearing support for a tube frame yarn-spool embracing in combination, a base member secured to the frame and affording a fulcral support, a bearing arm fulcrumed to swing thereon and formed at its free end with a journal-receiving bearing aper-

ture, the lower end of said arm being provided with stop members on opposite sides of the central axis disposed to engage a leaf spring arranged to exert counter-balancing rotative pressure on each stop member in 70 opposite directions when the bearing arm is in operative position, substantially as described.

2. A bearing support for the yarn spool of a tube-frame embracing in combination, a 75 supporting base, a bearing arm fulcrumed thereon said arm being provided at its free end with a bearing for the reception of the yarn-spool journal, and at its fulcral end with stop members disposed on opposite sides 80 of its fulcral axis, a flat spring mounted on the base to oppose a yielding pressure against said stop members and thereby maintain the arm yieldingly in operative position, substantially as described.

3. A bearing support for the yarn spool of a tube-frame embracing in combination a bearing arm pivotally mounted on the frame and provided with a journal-bearing orifice at its free end and its other end projecting beyond and bestriding the pivotal axis, and a spring mounted on the frame adjacent to the pivotal axis in position to engage the bestriding portions of the bearing arm on opposite sides of the axis and exert a yielding pressure tending to maintain the arm in proper operative position without exerting endwise pressure against the spool, substantially as described.

4. A bearing support for the yarn spool of a tube frame embracing in combination a base adapted to be secured to the carrier bar of a tube-frame and having eyes for supporting a pin, an axial fulcral pin inserted in said eyes, a leaf spring extending between said eyes beneath said pin, a bearing arm pivotally supported on said pin and provided at its free end with a bearing for receiving adjacent spool journals, said arms being provided with stop members arranged to engage said leaf spring and receive the thrust thereof on opposite sides of the fulcral axis, substantially as described.

5. A bearing support for the yarn spool of a tube-frame, embracing in its construction a bearing arm comprising two, face to face, members secured together, each having a flange-bordered opening in alignment with a similar opening in the other to form a journal-bearing, means for pivotally supporting said bearing arm on the tube frame carrier bar, and a spring mounted to exert a yielding thrust on each member tending to produce rotation of each member in opposition to the other to normally maintain the bearing arm under balanced pressure in operative position to support adjacent journals of a yarn spool, substantially as described.

6. In a tube frame for tuft weaving, the combination with a tube-carrying bar and 130

its overhead yarn spool comprising longitudinal spool sections arranged end to end, of an intermediate spool-supporting arm provided with a spool-journal bearing at its free end and pivotally mounted on said carrier bar to project between the adjacent heads of two spool sections, said arm being yieldingly maintained in normal operative position under spring tension against movement toward either spool head while capable of moving to either side to release the spool journal, substantially as described.

7. In a tube frame for tuft weaving, the combination of a carrier bar and its opposite end brackets for supporting the outside journals of a yarn-spool, an intermediate bearing arm arranged to afford bearing support for intermediate spool journals and arranged to swing into substantial parallelism with the top of the carrier bar for the purpose of facilitating the threading of the tubes, substantially as described.

8. In a tube frame for tuft weaving, the

combination of a carrier bar, its end brackets affording bearing support for the outside spool-journals and one or more intermediate spool-bearing arms normally held in position to support inner spool-journals and swingable into position substantially parallel with the carrier bar, and means for yieldingly maintaining said intermediate bearing arm in either of these two positions as may be desired, substantially as described.

9. In a tube frame for weaving, the combination with a carrier-bar and its end brackets provided with bearings for supporting a yarn-spool, an intermediate bearing arm mounted to normally support two adjacent journals of sections of the spool, said arm being movable from normal spool-supporting position to a position out of the path of threading needles during the tube-threading operation, substantially as described.

In witness whereof, I have subscribed the above specification.

WALTER BIXBY.
